(57) **CLAIM**

The ornamental design for pants with zippers, as shown and described.

DESCRIPTION

FIG. 1 is a front perspective view of the pants with zippers of our invention showing the location of the zippers;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8. is a front perspective view of a second embodiment of the design of FIG. 1, the only difference being the style of the zippers.

The broken lines shown directly on the surface of the claimed article, throughout the views, represent stitching and form no part of the ornamental design.
